(57) **CLAIM**

The ornamental design for a magnetic field generating device for use in MRI, as shown and described.

DESCRIPTION

FIG. 1 is a perspective view of a magnetic field generating device for use in MRI;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 4 Drawing Sheets

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 461,249 S
DATED : August 6, 2002
INVENTOR(S) : Tsuzaki et al.

Page 1 of 1

It is certified that error appears in the above-identified patent and that said Letters Patent is hereby corrected as shown below:

Title page.

Item [73], add assignee:

-- **Hitachi Medical Corporation, Tokyo, Japan** --

Signed and Sealed this

Fifth Day of November, 2002
